UNITED STATES PATENT OFFICE.

FRED I. LONG, OF GREATFALLS, MONTANA.

CUFF-HOLDER.

SPECIFICATION forming part of Letters Patent No. 716,728, dated December 23, 1902.

Application filed March 20, 1902. Serial No. 99,191. (No model.)

To all whom it may concern:

Be it known that I, FRED I. LONG, a citizen of the United States, residing at Greatfalls, in the county of Cascade and State of Montana, have invented certain new and useful Improvements in Cuff-Holders, of which the following is a specification.

This invention relates to cuff-holders, and has for one of its objects to make the bar thereof of a non-metallic material to obviate the liability of the same soiling an article of apparel with which it comes in contact.

A further object of the invention is to produce a new and improved clasp capable of being used in connection with the bar to form a cuff-holder and which is adapted to various uses independent of the bar, as on a garter or any supporting device.

A still further object of the invention is to provide improved fastening means for the clasp whereby the jaws thereof may be locked in their closed position to secure a firm grip upon an article of apparel.

The invention consists of the novel construction, combination, and arrangement of parts hereinafter fully described and claimed.

In the drawings, Figure 1 is a perspective view of a clasp constructed in accordance with my invention. Fig. 2 is a transverse sectional view thereof. Fig. 3 is a perspective view of a cuff-holder constructed in accordance with my invention.

Referring to the drawings, *a* designates the bar of the cuff-holder and is made of some non-metallic material, as vulcanized rubber, bone, or any suitable composition which may serve to accomplish the desired end, which is to prevent the bar soiling the clothes with which it comes in contact. The bar carries upon its outer end a rigidly-mounted button *b*, made of the same material as that of which the bar is formed, and has the shank thereof rectangular in form to prevent the button turning in the buttonhole, whereby all movement of the cuff upon the holder is obviated. The opposite end of the bar is provided with a clasp, to be hereinafter fully described.

1 and 2 designate the jaws of the clasp and are provided intermediate their ends with 50 cut-out portions 3 to permit elongated holding-jaws 4, formed thereby, to overlap each other and which may have their meeting faces

roughened to enable the clasp to secure a firm grip. The jaws are provided upon their outer edges with flanges 5, formed integral therewith, and journaled in perforations therein is a pintle 6, upon which is mounted a coiled spring 7, having the free ends thereof bearing against the inner faces of the jaws to normally keep the holding-jaws 4 separated. The jaws have stamped up therefrom, adjacent the cut-out portions 3, lugs 8, having perforations for the reception of the pintle 6, whereby, in connection with the flanges 5, the jaws are provided with a perfect pivotal connection. The pintle 6 may be provided with a threaded extension 9, projecting beyond one of the flanges 5, to receive the bar *a* to form the cuff-holder. The jaws 1 and 2 have their free ends downwardly formed and slitted to provide leaves 13 and 14, the latter being bent to form barrels 15 and 16, and the leaves 12 form spring-fingers, (designated, respectively, 12^a and 12^b.) The barrels 15 are adapted to receive the bent ends of a bail 17, thereby pivotally connecting the same to the clasp, and which is adapted to receive the free end of an article, such as a ribbon, constituting part of a garter to secure the clasp thereto.

I do not wish it to be understood that I limit myself to the application of the clasp to a garter or a cuff-holder, as it will be perceived that the same is applicable to any use to which a clasp is adapted. 80

The leaf 12^a has struck up therefrom a laterally-projecting tang 18, the purpose of which will be explained hereinafter. 85

The barrels 16 have rigidly mounted therein a bolt 19, carrying a pivoted finger 20, provided with a slot 21 for the reception of the tang 18 when the jaws are caused to approach each other to lock the clamping-jaws 4. The pivoted finger 20 normally rests against the spring-finger 12^a, whereby its inner face is kept in contact with the free end of the finger 12^a to provide a relative spring action between the pivoted finger 20 and finger 12^a. It will be perceived that the pivoted finger 20 is situated between the spring-fingers 12^a and 12^b and that their tendency is to exert an opposite pressure thereon and that when the jaws are caused to approach each other the pivoted finger will follow the curvature of the finger 12^a and cause the slot 21 to receive the

tang 18, which is normally held in contact with the upper wall thereof through the medium of the spring 7.

It will be obvious from the above description, taken in connection with the accompanying drawings, that I provide a cuff-holder and a clasp which will accomplish the desired results, and is cheap, durable, and efficient.

Having thus described the invention, what is claimed as new is—

1. In a cuff-holder, the combination with a bar provided with a button, of a clasp comprising jaws having a pivotal connection, one of said jaws having the rear extremity thereof downwardly bent to provide a spring-finger, a tang carried by the finger, a finger carried by the other jaw, and provided with an opening to receive the tang, and means for retaining the last-mentioned finger in position to permit of the automatic reception of the tang by the opening, when the rear ends of the jaws are moved toward one another, to lock the jaws in closed position.
2. In a cuff-holder the combination with a bar provided with a button, of a clasp comprising jaws having a pivotal connection, and the rear ends thereof provided with spring-fingers, one of the spring-fingers having a tang, and a pivoted finger secured to one of the jaws to be normally held in position to engage the tang by the other spring-finger.
3. In a cuff-holder the combination with a bar provided with a button, of a clasp comprising jaws having a pivotal connection and the rear ends thereof provided with spring-fingers and barrels, one of the fingers having a tang, a bail journaled in one series of the barrels, a bolt carried by the other series of barrels, and a pivoted finger secured to the bolt, and provided with a slot to receive the tang.
4. In a cuff-holder the combination with a bar provided with a button, of a clasp comprising jaws having a pivotal connection and

the rear ends thereof slotted forming leaves 45 to provide spring-fingers and barrels, one of the fingers having a tang, a bail carried by one series of the barrels, a bolt carried by the other series of barrels, and a pivoted finger carried by the bolt and provided with a slot 50 to receive the tang.

5. In a cuff-holder, the combination with a bar provided with a button, of a clasp comprising jaws having a pivotal connection, a finger carried by one of the jaws, a tang carried by the finger, and a finger provided with an opening and secured to the other jaw to be retained in position to permit of the automatic reception of the tang by the opening, when the rear ends of the jaws are moved toward one another, to lock the jaws in closed position.

6. In a cuff-holder, the combination with a bar provided with a button, of a clasp comprising jaws having a pivotal connection, a finger carried by one of the jaws, a tang carried by the finger, a finger pivotally secured to the other jaw, and provided with an opening, and means for retaining the pivoted finger in position to permit of the automatic reception of the tang by the opening, when the rear ends of jaws are moved toward one another, to lock the jaws in closed position.

7. In a cuff-holder, the combination with a bar provided with a button, of a clasp comprising jaws having a pivotal connection, spring-fingers formed integral with the jaws at right angles thereto, one of the fingers being provided with a tang, and a pivoted finger having an opening and adapted to be held in position by one of the spring-fingers to engage the tang.

In testimony whereof I affix my signature in presence of two witnesses.

FRED I. LONG.
